UNITED STATES PATENT OFFICE

159,600

COMBINED INFANT'S CRIB AND STORAGE CHEST

George H. Chilson, Hollydale, Calif.

Application June 24, 1949, Serial No. 3,510

Term of patent 14 years

(Cl. D5—5)

To all whom it may concern:

Be it known that I, George H. Chilson, a citizen of the United States, residing at Hollydale, in the county of Los Angeles and State of California, have invented a new, original, and ornamental Design for Combined Infant's Crib and Storage Chest, of which the following is a specification, reference being had to the accompanying drawing, forming part thereof.

Figure 1 is a perspective view of a combined infant's crib and storage chest, showing my new design. In this view, the article is illustrated in its closed arrangement.

Figure 2 is a view similar to Figure 1, but illustrating the article with its crib and upper storage compartments open.

The two sides of the device are of similar design, and the back is closed throughout its entire extent by a plain, continuous, flat surface.

I claim:

The ornamental design for a combined infant's crib and storage chest, substantially as shown and described.

GEORGE H. CHILSON.
